UNITED STATES PATENT OFFICE.

ERNEST E. HEINTZ, OF DETROIT, MICHIGAN, ASSIGNOR TO TERNSTEDT MANUFACTURING COMPANY, OF DETROIT, MICHIGAN, A CORPORATION OF MICHIGAN.

WINDOW-REGULATOR CLUTCH.

Application filed August 23, 1922. Serial No. 583,721.

To all whom it may concern:

Be it known that ERNEST E. HEINTZ, a citizen of the United States, residing at Detroit, in the county of Wayne and State 5 of Michigan, has invented certain new and useful Improvements in Window-Regulator Clutches, of which the following is a specification.

This invention relates to a window regulator. The improvement provides a new 10 form of clutch which positively locks the window against movement except that originating through the crank handle. Clutches for this purpose are not broadly 15 new. It is believed, however, that the clutch hereinafter described and claimed is about as cheap and simple a mechanical construction as could be conceived to accomplish the result desired.

20 In the drawings—

Fig. 1 is an inside elevation of an automobile, closed body door with the trimming removed.

Fig. 2 is a detail of the top parts of the 25 window regulator, showing the clutch in repose.

Fig. 3 is a sectional view on line 3—3 of Fig. 2.

Fig. 4 is a view similar to Fig. 2, showing 30 the clutch parts under operation through the crank handle.

Fig. 5 is a similar view, showing the clutch parts locked by forces originating in the window.

35 Fig. 6 is a sectional view on line 6—6 of Fig. 3.

Fig. 7 is a perspective of the crank shaft.

Fig. 8 is a perspective of the driving sleeve.

40 *a* designates the usual upper plate provided in window regulators, *b* represents the large driven gear wheel and *c* the upper sprocket on which runs the chain *d*. This large gear is driven by the pinion *e*. This 45 is merely one example of window regulator construction. Various other kinds could be used, such as a pulley wheel and cable type.

A hollow post *f* is secured to the window 50 regulator plate by the nut *g*. On this post is rotatably supported the pinion *e*, the end of the crank shaft *h* fits into the interior of the hollow post so as to be aligned therewith. This crank shaft is provided with a 55 key portion *i* that fits into the key slot *j*

of the driving sleeve *k*. This driving sleeve is provided with a slot *m*, which forms shoulders to engage with the coil now to be described.

The clutch per se includes the slotted 60 driving sleeve, the post *f*, and the coil *n*. This coil *n* is coiled about the post *f* and has two ends *o* and *p* turned up and outwardly. The clutch parts are shown in repose in Fig. 2. Now as the crank shaft, 65 which is connected to the crank *q* is rotated, the driving sleeve *k* is rotated and this presses against the inside of the coil end *o*. This tends to open up the coils and release the coil from the stationary post. The coil 70 end *o* is driven by the driving sleeve up against the pin *s*, which is secured in the pinion *e*. The clutch coil will rotate freely on the post and the driving sleeve will drive the driven pinion *e*. Precisely the 75 same operation occurs when the crank handle is operated in the opposite direction, except that the driving sleeve drives through the coil end *p*.

A force originating in the window which 80 tends to drive the regulator parts reversely immediately locks the clutch parts handle. This operation is detailed in Fig. 5 where the pin becomes a driving pin by reason of 85 any force originating in the window. Movement of the pin in either direction tends to wind the coils up on the shaft, in other words, constrict the coils on the shaft. This produces a binding frictional action 90 that locks the regulator.

Nothing much simpler than this plain coil could be conceived to accomplish the purpose in view. It is very much cheaper to manufacture than any clutch with which I am acquainted. No expenses or accurate 95 machine work is necessary as is common with clutches that have various sliding or rotating interlocking parts. No particular accuracy in the manufacture of the parts is required. The driving sleeve and the crank 100 shaft can be ordinary automatic screw machine parts that can be turned out on a large production scale at a small cost.

What I claim is:

1. In a window regulator, a clutch, having in combination a driven member provided with a projecting pin, a driving member in the form of a slotted sleeve, a stationary post, and a coil rotatable on said post and provided with projecting ends 110

which can be engaged both by the shoulders formed by the slot in the actuating sleeve and by the driven pin, whereby actuation originating from the driving sleeve opens the coils about the stationary post, and permits free driving of the driven member, while actuation originating in the driven member causes the pin to engage the coil end to bind the spring upon the post and lock the clutch parts.

2. In a window regulator, a clutch having in combination a driven member provided with a pin, a driving member provided with an opening, a stationary member, and a coil interposed between the driving and the driven members and provided with projecting ends which are projected through the opening in the driving member, the pin carried by the driven member adapted to engage with either projecting end of the coil, whereby actuation originating from the driving member causes one wall of the driving member opening to engage one of the projecting ends of the coil to open the coils about the stationary post to permit free driving of the driven member, while actuation originating in the driven member causes the pin to engage one projecting coil end to bind the coil upon the stationary post to lock the clutch parts.

3. In a window regulator, a clutch having in combination, a stationary post, a driven member rotatably supported on the post and provided with a pin, a driving sleeve rotatably supported by said post and provided with a slot, and a spring coil interposed between the driving and driven members and provided with projecting ends arranged to project in said slot, each end of said coil end interposed between said pin and one of the shoulders formed by the slot in the driving sleeve, whereby actuation originating from the driving sleeve opens the coils about

the stationary post, and permits free driving of the driven member, while actuation originating in the driven member causes the pin carried by the driven member to engage the coil end to bind the spring coil about the post to lock the clutch parts.

4. In a window regulator, a clutch and bearing, comprising a hollow stationary post, a crank shaft having its end rotatably supported in the hollow interior of the said post and provided with a driving member engaging about the outside of the said hollow post, a pin secured to the driven member, and a coil spring fitted on the exterior of the hollow post and having its two ends turn up, the pin engaging between the two ends of the coil and the driving member engaging on both sides of the coil ends.

5. In a window regulator, a clutch and bearing having in combination a hollow post, a driven member rotatably supported upon the hollow post; and provided with a projecting pin, a crank shaft having its end portion rotatably journaled in the hollow interior of the post, means for preventing said crank shaft from withdrawing lengthwise out of said hollow post, a coil spring fitted about the exterior of the hollow post and having a pair of outwardly projecting ends, and a driving member secured to the crank shaft, the said projecting pin, the projecting spring ends, and the driving member arranged so that actuation in either direction by the pin serves to bind the spring on the stationary post while actuation by the driving member engaging against either spring end serves to open up the coils and permit rotation of the driving member and the driven member.

In testimony whereof I affix my signature.

ERNEST E. HEINTZ.
